UNITED STATES PATENT OFFICE.

REMSSEN T. WILLIAMS, OF GREAT NECK, NEW YORK.

PUTTY.

Application filed October 7, 1922. Serial No. 592,993.

To all whom it may concern:

Be it known that I, REMSEN T. WILLIAMS, a citizen of the United States of America, and resident of Great Neck, Long Island, in the county of Nassau and State of New York, have invented certain new and useful Improvements in Putties, of which the following is a specification.

This invention is a putty particularly adapted for use by motorcyclists. When a person rides a motorcycle the inner sides of the legs between the knee and the ankle are positioned directly adjacent the motor of the vehicle which, through continuous running, becomes highly heated and subjects the rider to considerable discomfort. For this reason it is the practice of motorcyclists to wear putties to protect the limbs against the heat from the motor, but even when heavy leather putties are worn, it is not uncommon, after continuous riding, for the highly heated motor to cause blistering of the rider's limbs.

With these considerations in mind, the object of the present invention is to provide a putty which is air cooled. In its preferred practical form, the putty of this invention is so constructed that that portion thereof which overlies the inside of the leg is jacketed, preferably through the incorporation thereinto of a plurality of flues or air ducts and air is caused to circulate through this jacket or flues for the purpose of keeping the limbs of the operator cool.

This invention may be incorporated in a putty especially constructed for the purpose or may be embodied in an attachment which may be associated with any conventional form of putty.

In one of its preferred practical forms, the invention embodies a putty, the inside leg portion of which embodies two spaced walls forming an intermediate jacket or chamber which is divided into a series of ducts or flues by a plurality of spacing members. When these spacing members extend in a substantially vertical direction, they are preferably extended beyond the lower edge of either the inner or outer wall to form deflectors, which, as the rider passes through space, serve to deflect air upwardly through the several flues, the air being discharged through the open tops of said flues. This circulation of air effects a thorough cooling of the inner wall and entirely eliminates the objectionable heating referred to.

Features of the invention, other than

those adverted to, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a back view of a putty embodying the present invention.

Figure 2 is a side elevation of the same putty as viewed from the inner side of the leg.

Figure 3 is a section on the line 3-3 of Figure 2.

Figures 4 and 5 illustrate modified cross sections which may be employed.

Figure 6 is a view similar to Figure 2, but illustrating a modified form of putty.

Figure 7 is a section on the line 7-7 of Figure 6; and,

Figure 8 is a perspective view illustrating the present invention as incorporated in an attachment adapted to be associated with any conventional form of putty.

Referring more particularly to Figures 1 to 3, inclusive, 1 designates a putty, which, in practice, may be made from leather, canvas, a combination of these materials or of any other suitable material. That portion of the putty which passes about the outside of the leg is made in the form of a single wall, designated in the drawings by the reference character 2, while that portion of the putty which passes about the inner side of the leg is made with inner and outer walls 3 and 4, respectively, which are spaced apart so that the inner side of said putty may be said to be jacketed. The walls 3 and 4 may be spaced apart by different means, but in the showing of Figures 1 to 3, this spacing is accomplished by means of substantially vertical partitions 5, which extend from the upper edge of the putty, downwardly between the inner and outer walls 3 and 4 and project beyond the lower edge of the outer wall 4, as best shown in Figures 1 and 2.

The projecting portions 6 of these partitions are graduated in length, the forward projection being the shortest and the rearward projection being the longest, as shown in Figure 2 and said projections are preferably curved in a forward direction, so as to form deflectors, whereby air is directed into the space between the inner and outer

walls 3 and 4 and flows upwardly through the flues 8 formed between the successive partitions. In order that the projections or deflecting portions 6 may be reinforced, the inner wall 3 is preferably extended downwardly, as shown at 7 to the lower ends of the several deflectors 6 and the deflectors are secured thereto by stitching, riveting or otherwise. The partitions 5 are similarly 10 maintained in position by stitches, rivets or in any other suitable manner, so that they are properly spaced apart and maintained in position so as to space the walls 3 and 4 apart.

15 When putties embodying the invention as described and shown in Figures 1 to 3 are worn by a motorcyclist, the chambered or jacketed portions of the putties overlie the inner sides of the rider's legs and as the 20 rider passes through space, the deflectors 6 direct air into the ducts 8, so that the air is circulated upwardly through these ducts or flues and leaves at the open tops thereof, so that the putty is air cooled and even though 25 the outer wall 4 comes into direct contact with the hot motor, the heat therefrom will not be transmitted to the driver's legs.

Any suitable means may be employed for 30 binding the putty about the leg, such as the single strap that is sometimes worn for this purpose, although a plurality of straps or clasps may be employed as in the conventional putty.

In Figure 4, I have illustrated a modified 35 form of construction which differs from the construction of Figures 1 to 3 only in the means for spacing the inner and outer walls 3 and 4 apart. In the construction of Figures 1 to 3, a plurality of partitions 5 are 40 shown, while in the construction of Figure 4, a corrugated intermediate wall 5^a is employed. Portions of this wall may extend below the lower edge of the outer wall 4 and 45 form deflectors corresponding to the deflectors 6 and functioning in the same manner.

In the construction of Figure 5, the structure is substantially as shown in Figure 4, except that the outer wall 4 is omitted, the 50 ducts 8^a being formed between corrugations of the wall 5^a. If desired, the structure of Figure 4 may be reversed as to the walls 3 and 5^a. That is to say, the inner wall 3 may be corrugated and the outer wall 5^a may be made smooth.

55 In Figures 6 and 7, a further modified form of construction which may be employed is illustrated and in this construction the flues 8^b extend in a horizontal direction around the inner side of the putty, instead 60 of vertically as in the preceding figures. In this embodiment, the putty is constructed with an inner wall 3, an outer wall 4 and horizontal partitions 5^b, which divide the jacketed inner side of the putty into a plurality of ducts 8^b. The forward end of each

of these ducts is open as shown at 9 and the outer wall 4 is flared outward adjacent the opening to produce a deflector 6^b, so that air is directed by the deflectors 6^b into the inlet ends 9 of the several ducts and after 70 flowing through said ducts is discharged at the rear ends 10 thereof.

In Figure 8 of the drawings, the invention is illustrated in the form of an attachment which may be associated with any conventional form of putty. In this showing, 75 it comprises an outer wall member 4 on which are mounted a plurality of partitions 5. The structure is substantially the same as shown in Figures 1 to 3, except that the 80 inner wall 3 is entirely omitted and the outer wall member 4 is of such size as to extend only substantially one-half around the leg. The attachment may be associated with any putty or, as a matter of fact, may 85 be associated with a leg on which no putty is worn, by merely positioning the outer wall member about the inside of the leg and binding it in position by means of cooperating straps and buckles 11 and 12. When 90 worn in this manner, the partitions 5 serve to space the wall member 4 from the leg or putty and form intermediate ducts or flues through which air is circulated in the manner described.

95 In carrying out the invention in practice, deflectors for causing the circulation of air through the flues are preferably constructed as shown at 6 or 6^b. I am aware however that the deflectors might be otherwise constructed and accordingly do not limit the invention to the specific constructions illustrated.

The accompanying drawings and foregoing detailed description set forth the invention in its preferred forms but the invention is to be understood as broadly novel as is commensurate with the appended claims.

Having thus fully described the invention, what I claim as new and desire to secure by Letters Patent is:

1. A device of the class described embodying a leg covering adapted to overlie the inside of the leg, means for spacing said leg covering from the leg to form an intermediate air space, and deflector means adapted, when the wearer moves through space, to direct air into the air space for the purpose of keeping the leg cool.
2. A device of the class described embodying a leg covering adapted to overlie the leg, means for spacing that portion of the leg covering which overlies the inside of the leg from the leg and to divide the intervening space into a plurality of flues open at their opposite ends, and deflectors associated with each flue and adapted, when the wearer moves through space, to direct air into one end of each flue, so that the air is circulated through the flues and discharged from the

opposite ends thereof for the purpose of keeping the leg cool.

3. A device of the class described embodying a leg covering provided in that portion which overlies the inside of the leg with a plurality of flues open at their opposite ends, and deflecting means associated with the flues and adapted when the wearer moves through space to direct air currents into the flues so that said air currents will pass through the flues and keep the leg cool.

4. A leg covering, the inside leg portion of which comprises two spaced walls forming between them an air space, means for spacing said walls apart and for dividing the air space into a plurality of flues, which are open to the external atmosphere at their opposite ends to permit the circulation of air through said flues for the purpose of keeping the leg cool.

5. A leg covering, the inside leg portion of which comprises two spaced walls forming between them an air space, means for spacing said walls apart and for dividing the air space into a plurality of flues, which are open to the atmosphere at their opposite ends, and a deflector associated with one end of each flue to cause the circulation of air through the flues when the wearer moves through space.

6. A putty adapted to encircle the leg and provided in that portion which overlies the inside of the leg with double walls spaced apart to provide an intermediate air space having air inlet and outlet openings both of which communicate with the atmosphere exteriorly of the putty, whereby air may circulate through said air space to keep the leg cool.

7. A putty adapted to encircle the leg and provided in that portion which overlies the inside of the leg with double walls spaced apart to provide an intermediate air space having air inlet and outlet openings both of which communicate with the atmosphere exteriorly of the putty, and means for causing the circulation of air through said air space for the purpose of keeping the leg cool.

8. A putty adapted to encircle the leg and provided in that portion thereof which overlies the inner side of the leg with double walls spaced apart, means for spacing said walls apart and for dividing the space between said walls into a plurality of flues, which are open at their opposite ends to the atmosphere exteriorly of the putty, and deflector

means associated with each flue and adapted, when the wearer moves through space, to direct air into said flues for the purpose of causing the circulation of air through said flues, whereby the inner side of the leg is kept cool.

9. A putty adapted to encircle a leg and provided in that portion thereof which overlies the inner side of the leg with double walls spaced apart to provide an intermediate air space, partitions for spacing said walls apart and for dividing said air space into a plurality of flues which extend from the top to the bottom of the putty, the lower end of each partition being extended to form a deflector, and the several deflectors being graduated so that the forward deflector is the shortest and the rear deflector the longest, whereby, when the wearer passes through space, the deflectors will direct air into the several flues and cause the circulation of air through such flues to keep the leg cool.

10. A putty adapted to encircle a leg and provided in that portion thereof which overlies the inner side of the leg with double walls spaced apart to provide an intermediate air space, partitions for spacing said walls apart and for dividing said air space into a plurality of flues which extend from the top to the bottom of the putty, the lower end of each partition being extended to form a deflector, and the several deflectors being graduated so that the forward deflector is the shortest and the rear deflector the longest, whereby, when the wearer passes through space, the deflectors will direct air into the several flues and cause the circulation of air through said flues to keep the leg cool, one of the walls of the putty being extended downwardly adjacent the deflectors and secured to said deflectors to reinforce them and maintain them in proper relative positions.

11. As a new article of manufacture, a putty formed with an insulating air space open to the atmosphere substantially as described.

12. As a new article of manufacture a putty formed with air channels open to the atmosphere substantially as described.

Signed by me at New York city this 5th day of October, 1922.
